UNITED STATES PATENT OFFICE

WILLIAM PLATTS KELLETT, OF NEW YORK, N. Y.

GOODS CONTAINER TRANSPORTATION MEANS

Application filed July 17, 1930. Serial No. 468,723.

The principal objects of the invention are, to facilitate the handling of movable goods containers on cars for transporting same between railway terminals, and to provide cars and containers equipped so that the containers will be securely held in position from lateral play, but which may be readily removed without binding, even when the railway cars may be standing on curves.

10 The principal features of the invention consist in the novel arrangement of the central caster wheel supports of the goods container with a gauge narrower than the gauge of the flanged guides of the car upon which 15 the container is mounted and correspondingly narrower than the gauge of the end sets of caster wheel supports, together with the novel flaring arrangement of guide flanges on the car deck to direct the flanged wheels of the 20 container on to the central runway.

In the drawings, Figure 1 is a plan view of the adjacent ends of a pair of railway cars having flanged runways for receiving wheeled goods containers, said cars being 25 arranged at the maximum angle of standard railway curves, the position of the container and its supporting caster wheels being shown on dotted lines on one end of a car.

Figure 2 is a similar plan view showing 30 in short dotted lines the position of a container spanning the adjacent ends of the two railroad cars and also showing the position of the container in long dotted lines when moved farther on to the second car.

35 Figure 3 is an enlarged and elevational view of the deck of the car showing the location of both end and inside caster wheels located between the retaining deck flanges.

In the carrying out of this invention the 40 railway car is provided with a deck 1 formed preferably of steel plate having the central portion 2 thereof depressed to form a central channel with slightly bevelled edge flanges 3. These bevelled edges are flared outwardly 45 at the ends 4.

The goods container, which may be of any 50 desirable construction, is provided with a plurality of sets of caster wheels, the sets 5 and 6 being arranged close to the ends, while the sets 7 and 8 are arranged substantially equi-

distant from the ends and equidistant from each other.

The longitudinal spacing of the caster wheels is such that the set of wheels 8 will, when the container is being moved from one car to another, remain on the deck surface until the adjacent end set 6 has reached the deck of the adjacent car, or vice versa the set 7 will remain in engagement with the car deck until the set 5 has reached the other car in moving in the other direction. This provides a cantilever support for the container which prevents it from tipping endways.

The end sets of casters 6 and 7 are spaced apart so that when the wheels are set parallel with the sides of the container, the side rims of the outer wheels will engage the bevelled flanged edges 3 of the deck plate, thus preventing any side play.

The inner sets of casters 7 and 8 are, however, of a narrower gauge than the end sets and they are spaced inward from the flanges 3 at a distance sufficient to permit the caster to rotate. This narrower gauge arrangement of the inner sets of casters permits the container to be rolled from one car to another when standing on curved sidings without the central caster sets binding upon the side flanges, that is to say, the set of casters at the end passing on to another car will swing 50 out of the central alignment of the first car and the inner sets of casters will permit this side swing without binding on the flanges, but they retain their faculties of supporting the load of the container equally as well.

The invention is extremely simple, but it is nevertheless a very important factor in the handling of freight containers which are operated longitudinally of a flanged car deck, and the arrangement of the casters in this manner permits the unloading of the containers lengthwise of the train, irrespective of whether the train is standing on a straight or curved track.

It is of course an important feature in conjunction with such caster arrangement that the central depression of the car deck shall be clear of other obstructions to interfere with the proper movement of casters in moving the containers from one car to another.

What I claim as my invention is:—

1. A goods container having wheel supports spaced longitudinally of the container, the end pairs of said wheel supports being of a wider gauge than the others, and a car having side flanges adapted to engage the wider gauge wheel supports.
2. Railway cars having car decks formed with raised longitudinal side flanges forming a runway, containers having wheel supports at the ends to engage the flanges of said runways, and wheel supports intermediate of their length of a lesser gauge than the end wheel supports.
3. Goods container transport means comprising railway car decks having depressed parallel sided longitudinal runways formed with flaring ends, goods containers having wheel supports arranged in pairs adjacent to the ends, said wheel supports being of a gauge to bring the flanges of the wheels into engagement with the flanges of the runways whereby said goods containers will be supported against lateral displacement, and sets of wheels spaced between the end wheels and of a narrower gauge than said end wheels to permit the containers to be swung at an angle to the runway in passing from the car.
